(57) **CLAIM**

The ornamental design for a modular lighting set as shown and described.

DESCRIPTION

FIG. 1 is a top perspective view of a first component of the modular lighting set;

FIG. 2 is a bottom perspective view of the first component; FIG. 3 is a side elevational view of the first component, the left, right, front, and back sides of the first component being identical to one another;

FIG. 4 is a top plan view of the first component;

FIG. 5 is a bottom plan view of the first component;

FIG. 6 is a top perspective view of a second component of the modular lighting set;

FIG. 7 is a bottom perspective view of the second component;

FIG. 8 is a side elevational view of the second component, the left, right, front, and back sides of the first component being identical to one another;

FIG. 9 is a top plan view of the second component;

FIG. 10 is a bottom plan view of the second component;

FIG. 11 is a top perspective view of a third component of the modular lighting set;

FIG. 12 is a bottom perspective view of the third component; FIG. 13 is a side elevational view of the third component, the left, right, front, and back sides of the first component being identical to one another;

FIG. 14 is a top plan view of the third component;

FIG. 15 is a bottom plan view of the third component;

FIG. 16 is a top perspective view of a fourth component of the modular lighting set;

FIG. 17 is a bottom perspective view of the fourth component;

FIG. 18 is a side elevational view of the fourth component, the left, right, front, and back sides of the first component being identical to one another;

FIG. 19 is a top plan view of the fourth component;

FIG. 20 is a bottom plan view of the fourth component;

(Continued)

FIG. 21 is a perspective view of a first modular combination of the modular lighting set, with the first component in both uplight and downlight positions;

FIG. 22 is a perspective view of a second modular combination of the modular lighting set, with the first component in the uplight position and the second component in the downlight position;

FIG. 23 is a perspective view of a third modular combination of the modular lighting set, with the first component in the uplight position and the third component in the downlight position;

FIG. 24 is a perspective view of a fourth modular combination of the modular lighting set, with the first component in the uplight position and the fourth component in the downlight position;

FIG. 25 is a perspective view of a fifth modular combination of the modular lighting set, with the second component in the uplight position and the first component in the downlight position;

FIG. 26 is a perspective view of a sixth modular combination of the modular lighting set, with the second component in both uplight and downlight positions;

FIG. 27 is a perspective view of a seventh modular combination of the modular lighting set, with the second component in the uplight position and the third component in the downlight position;

FIG. 28 is a perspective view of an eighth modular combination of the modular lighting set, with the second component in the uplight position and the fourth component in the downlight position;

FIG. 29 is a perspective view of a ninth modular combination of the modular lighting set, with the third component in the uplight position and the first component in the downlight position;

FIG. 30 is a perspective view of a tenth modular combination of the modular lighting set, with the third component in the uplight position and the second component in the downlight position;

FIG. 31 is a perspective view of an eleventh modular combination of the modular lighting set, with the third component in both uplight and downlight positions;

FIG. 32 is a perspective view of a twelfth modular combination of the modular lighting set, with the third component in the uplight position and the fourth component in the downlight position;

FIG. 33 is a perspective view of a thirteenth modular combination of the modular lighting set, with the fourth component in the uplight position and the first component in the downlight position;

FIG. 34 is a perspective view of a fourteenth modular combination of the modular lighting set, with the fourth component in the uplight position and the second component in the downlight position;

FIG. 35 is a perspective view of a fifteenth modular combination of the modular lighting set, with the fourth component in the uplight position and the third component in the downlight position;

FIG. 36 is a perspective view of a sixteenth modular combination of the modular lighting set, with the fourth component in both uplight and downlight positions; and,

FIG. 37 is a collection of side elevational views illustrating all of the modular combinations of the modular lighting set. The broken lines in the drawing figures illustrate portions of the article which form no part of the claimed design.

1 Claim, 30 Drawing Sheets
